Fig. 10.

A technical drawing of a mechanical part, likely a bracket or frame. The part is shown in three views: a front view on the left, a top view in the center, and a side view on the right. The drawing includes several labeled features: **B1** at the top left, **B2** in the center, **B3** at the top center, **B4** at the top right, **B5** in the middle right, and **B6** at the bottom right. There are also dashed lines indicating hidden features and a horizontal line with arrows at the bottom.

UNITED STATES PATENT OFFICE.

CYRUS S. OLDRYD, OF CINCINNATI, OHIO.

MINING MACHINE.

Application filed January 8, 1921. Serial No. 435,821.

To all whom it may concern:

Be it known that I, CYRUS S. OLDRYD, a citizen of the United States, residing at Cincinnati, in the county of Hamilton and State of Ohio, have invented a new and useful Improvement in Mining Machines, of which the following is a specification, reference being had to the accompanying drawing.

My improvement relates particularly to machines used for cutting into upright walls of coal, rock, or similar material, the machine comprising cutting means actuated by the machine and projected endwise into the wall of coal, or other material, and then moved sidewise to make a sweeping cut.

The object of my improvement is to provide a machine by which the cutting means may be made to cut kerfs into the wall as follows: (1) horizontally along the floor level and horizontally at other levels as high as the machine can reach; (2) vertically and parallel to the general forward course of the machine within a certain range and diagonally to said course within a more extended range; (3) obliquely toward the right or toward the left within a certain range; (4) annularly around a horizontal axis; and (5) in a variety of curves.

Another object of the invention is to provide mechanism comprising cutting mechanism which may be lowered below and raised above the level of the track supporting the machine and operated for cutting in such low position, in order that the under-cutting may be at the level of the floor upon which the track rests.

By way of general statement, it may be said that the machine consists of (1) a truck having supporting or traction wheels adapted to rest on an ordinary rail track or on a floor; (2) a longitudinal body supported by the truck and turnable on an upright axis; (3) a neck located at the front of said movable body and rotatable on a horizontal axis extending lengthwise of the machine and approximately in an upright plane cutting midway between the track rails; (4) a head supported upon the neck and rotatable thereon on an axis which is perpendicular to the axis upon which the neck rotates; (5) a tongue comprising a cutting mechanism support and cutting mechanism, said support being supported upon said head for movement toward and from the axis of rotation of said neck, whereby the cutting mechanism, supported by said support, is supported in sub-

stantially horizontal position and movable bodily toward and from the axis of rotation of the neck and for bodily orbital movement around said axis.

The truck, body, neck, head, and said support and the cutting means being thus related to each other, the cutting means may be put into a variety of positions and through a variety of movements while it is cutting, as will hereinafter be described.

In the accompanying drawings:

Fig. 1 is an elevation of the right-hand side of a machine embodying my improvement;

Fig. 2 is a plan of the same machine;

Fig. 3 is a front elevation, the cutting tool being broken away;

Fig. 3^a is a rear elevation, parts being broken away;

Figs. 4^a and 4^b are an upright, longitudinal section, the section occupying two sheets, Fig. 4^b being a continuation rightward of the structure shown in Fig. 4^a;

Fig. 5 is a plan of the truck platform;

Fig. 6 is an elevation of the right-hand side of said platform;

Fig. 7 is a plan of the body of the machine separated from the truck and other parts;

Fig. 8 is an elevation of the right-hand side of said body;

Fig. 9 is an upright, transverse section on the line, 9-9, of Figs. 7 and 8, looking toward the right;

Fig. 10 is a front elevation of the body shown in Figs. 7 and 8, portions being broken away;

Fig. 11 is a bottom view of the top plate of the body of the machine;

Fig. 12 is an elevation of the right-hand edge of said plate, a part being broken away;

Fig. 13 is an elevation of the front end of said plate;

Fig. 14 is a transverse, upright section on the line, 14-14, of Fig. 11;

Fig. 15 is an upright transverse section on the line, 15-15, of Fig. 11;

Fig. 16 is a horizontal section on the line, 16-16, of Figs. 4^a and 4^b;

Fig. 17 is a horizontal section on the line, 17-17, of Fig. 4^a;

Fig. 18 is an upright, transverse section on the line, 18-18, of Fig. 4^a;

Fig. 19 is an upright section on the line, 19-19, of Fig. 17;

Fig. 20 is a horizontal section on the line, 20-20, of Fig. 18;

- Fig. 21 is a horizontal section on the line, 21—21, of Fig. 18;
- Fig. 22 is a detached view of one of the members shown in Fig. 18;
- 5 Fig. 23 is a section on the line, 23—23, of Figs. 1, 2 and 4^b, looking toward the left;
- Fig. 24 is a side elevation of the neck, the detachable upper forward extension thereof being omitted;
- 10 Fig. 25 is a plan of said extension;
- Fig. 26 is a side elevation of said extension;
- Fig. 27 is a front elevation of said extension;
- 15 Fig. 28 is a plan of the neck shown in Fig. 24;
- Fig. 29 is an upright transverse section on the line, 29—29, of Fig. 4^b, looking toward the right;
- 20 Fig. 30 is a plan of the lower head section;
- Fig. 31 is a right-hand side elevation of said section;
- Fig. 32 is an upright longitudinal section 25 on the line, 32—32, of Fig. 30;
- Fig. 33 is a plan of a binding plate to be applied to the lower head section;
- Fig. 34 (Sheet 9) is a top view of the upright head section, portions being broken 30 away;
- Fig. 35 is a right-hand side elevation of said upper head section;
- Fig. 36 is an upright longitudinal section on the line, 36—36, of Fig. 34;
- 35 Fig. 37 is a horizontal section on the line, 37—37, of Fig. 4^b;
- Fig. 38 is a horizontal section on the line, 38—38, of Fig. 4^b;
- Fig. 39 is a section on the line, 39—39, of 40 Fig. 4^b, looking toward the left, portions being broken away;
- Figs. 40, 41, 42 and 43 are plans showing the cutting mechanism supported in different positions.
- 45 Referring to said drawings, A designates the truck. B designates the longitudinal body which is turnable on an upright axis on the truck. C designates the neck which is supported on the forward end of said body and rotatable on an axis which is horizontal and parallel to the body, B, and the track rails, R. D designates the head which is supported by said neck and rotatable thereon through approximately 180 degrees 50 on an axis which is perpendicular to the axis of the neck. E designates the tongue.
- The truck comprises supporting or traction wheels, A¹, which are in the form of ordinary mine car wheels and mounted on 55 axles, A². A³ is a horizontal platform supported upon said axles and upon which is supported the body, B. The platform is shown in the form of a rectangular parallelogram with downward-directed flanges along 60 its four edges.

At the forward end of the body is a front cross wall, B³. At its middle the upper portion of said wall is cut out to form the lower half of a bearing, B⁴.

Approximately midway between its front 70 and rear ends, the body has a rear cross wall, B⁵, which has a circular opening, B⁶, in horizontal axial alignment with the bearing, B⁴, in the cross wall, B³.

A top plate, B⁷, rests upon the cross walls, 75 B³ and B⁵. Said top plate is secured in position by bolts, B⁸, extending downward through said plate into the cross walls and also into the bottom of the body, B.

At the middle of the forward edge of the top plate is a downward extension, B⁹, fitting into the opening in the front cross wall, B³, and having in its lower end a half circular recess which forms the upper half of the bearing, B⁴, already described. 80

On the bottom of the body, B, a little way forward of the rear cross-wall and on the upright, middle, longitudinal plane of the machine is a trunnion, B¹, which extends downward into a bearing, A⁸, formed in the floor of truck. On the truck are rollers, A⁴, which extend above the upper face of the truck far enough to support the body free from the upper face of the truck. Thus the body is supported turn-table fashion on the truck for rotation on the upright axis of said trunnion. The means for turning said body will be described further on. 85

Below said trunnion is an upright housing, A⁷, having an upper, annular horizontal flange, A⁹, secured against the lower face of the platform by means of bolts or screws, A¹⁰. A shaft, A⁶, rests rotatably in the trunnion on the axial line of the trunnion. In the bottom of said housing is a bearing, A¹⁰, 100 which receives the lower end of the shaft, A⁶. On said shaft, just above said bearing is a worm, A¹¹, which meshes with a worm gear wheel, A¹², on a shaft, A¹⁴, resting in bearings, A¹³, formed in the housing, A⁷. Said shaft, A¹⁴, rests also in a bearing, A¹⁵, extending downward from the truck platform. (Figs. 4, 17 and 18). On the rear end of said shaft is a bevel gear wheel, A¹⁶. 105

Adjacent the gear wheel, A¹⁶, on the rear axle, A², are supported two bevel gear wheels, A¹⁷, facing toward each other and slidably lengthwise on the shaft and held against rotation on the shaft by a feather, A¹⁸. Said gear wheels have a common 110 grooved hub engaged by an arm, A¹⁹, on a shift lever, A²⁰. By means of said hub said wheels, A¹⁷, are spaced from each other so that by means of the shift lever either of said wheels may be brought into mesh with the gear wheel, A¹⁶, or both moved out of engagement with the wheel, A¹⁶. By means of the shaft, A⁶, and A¹⁴, and the axle, A², and the gear wheels associated therewith, 115 the truck axle, A², may be rotated in either 120 direction. The truck is supported by the 125

axles, A², and the gear wheels associated therewith, the truck axle, A², may be rotated in either 130

direction, at the will of the operator, for propelling the truck forward or backward. Power is transmitted to the shaft, A⁶, as will be hereinafter described.

5 At the rear of the gear cross wall, B⁵, a motor, B¹¹, is seated upon the floor of the body, B, and has a horizontal rotary axle, B¹², in axial alignment with the bearing, B⁴, in the front cross wall, B³; but said axle 10 ends before reaching said cross wall. Said axle has a bearing, B¹³, on a horizontal, transverse bridge, B¹⁴, supported by said side walls of the body, B. Near the motor and at the forward side of the rear cross 15 wall, B⁵, is a bevel gear wheel, B¹⁵, surrounding the axle, B¹², and immovably keyed thereto.

The upper end of the shaft, A⁶, is joined immovably to a circular plate or disk, A²⁸. 20 When said disk is rotated, the shaft, A⁶, is correspondingly rotated. Said disk rests on the upper end of the trunnion, B¹.

An annular internal gear wheel, B¹⁷, lies flatwise upon the plate, A²⁸, and is concentric with shaft, A⁶, and is secured to the plate, A²⁸, by means of rivets, B¹⁸. Immediately above the gear, B¹⁷, and on the same axis is another annular internal gear, B¹⁹, which is a little larger than the gear, B¹⁷, 30 and which is held against rotation by brackets, B²⁰, supported by the side walls of the body, B.

Within the internal gears, B¹⁷ and B¹⁹, and resting upon the plate, A²⁸, is an eccentric wheel, B²¹, extending to the upper level of the gear, B¹⁹. A stud, B²³, extends downward from the eccentric wheel, B²¹, into a bearing, B²⁴, on the axis of the shaft, A⁶. An eccentric gear, B²², loosely surrounds the eccentric wheel, B²¹, and meshes with the internal gear, B¹⁷. Also loosely surrounding the eccentric wheel, and resting upon the eccentric gear, B²², is a similar eccentric gear, B²⁵. The gear, B²⁵, is secured to the lower gear wheel, B²², by means of rivets, B²⁶, and it is a little larger in diameter than the eccentric gear, B²², so as to permit meshing with the upper internal gear, B¹⁹. Upon the upper face of the eccentric wheel, B²¹, is a bevel gear, B²⁷, meshing with the bevel pinion, B¹⁵, already described as surrounding the motor axle, B¹², adjacent the rear cross wall, B⁵. The bevel gear wheel, B²⁷, is secured to the upper cam wheel, B²⁸, by means of screw bolts, B²⁹. The gearing thus described, is already known to the art as an "epicyclic gearing." In the present structure it is employed for transmitting motion from the motor axle to the upright shaft, A⁶, at a reduced velocity.

It is to be observed that this gearing is to be used only when it is desired to move the machine bodily forward or backward on the track. When it is desired that the machine 65 shall remain stationary while the motor is

in action, the shift lever, A²⁰, is so set as to bring both bevel gear wheels, A¹⁷, out of engagement with the bevel gear wheels, A¹⁹, on the truck shaft, A¹⁴.

On the rear end of the truck, A, is a gear rack, A²¹, formed concentric to the upright axis of the body, B. On the lower face of the body, B, are two bearings, F², arranged on a line parallel to the length of the body. In said bearings rests a shaft, F¹. On the forward end of said shaft is fixed a spur gear wheel, F, which meshes with said gear rack. On the rear end of said shaft is a spur gear wheel, F³, which meshes with a smaller spur gear wheel, F⁴, on a motor, F⁵, which is seated on the floor of the body B. When the body is to be turned horizontally on its upright axis, the motor is set into motion in the appropriate direction to turn the body in the desired direction.

In describing the neck and the head, for convenience, it will be assumed that the neck has been so turned on its axis as to bring these parts into the position shown in Figs. 1, 3, and 4^b of the drawings, so that the portion of the neck which extends the farther from the longitudinal axis of the machine (the axial line of the motor, B¹¹, and the motor axis, B¹²) is directed to or toward the floor, such portion being, for convenience, designated the lower portions of the neck, while the portion which is then above said longitudinal axial line is designated the upper portion of the neck.

The neck, C, comprises a rigid horizontal journal, C¹, preferably integral with the other portions of said neck, which journal rests in the bearing, B⁴, which, as above described is formed in the forward cross wall, B³, and the downward extension, B⁹, of the top-plate. On the rear end of said journal is a worm gear wheel, C², which bears against the rear face of the transverse wall, B³. Above the level of the axis of the journal, C¹, the neck extends only to the height of the top-plate, B⁷. Below said axis, the neck (when the body is in its lower position) extends downward below the level of the track rails, R, and close to the portion of the floor which is in front of said rails, the neck thus extending below the supporting faces of the machine or the upper surface of the track rails as much as the sum of the height of the track rails plus the ties, T, upon which the rails are supported.

The neck, C, has a lower forward extension, C³, and an upper forward extension, C⁴, secured thereto. On a common axial line which is perpendicular to the axis of the neck, the extension, C³, has a bearing, C⁵, and the extension, C⁴, has a bearing, C⁶. The extension, C⁴, is detachable from the upright portion of the head. On each lateral edge, said extension has an upright groove, C⁷, each being

directed toward the other and receiving corresponding upright tongues, C⁸, fixed on the neck. The extension, C⁴, is put into position by placing it above the main portion of the neck, (when the extension, C⁴, is in the lower position) and then moving said extension downward, the grooves, C⁷, receiving the tongues, C⁸.

At approximately the height of the bottom of the body, A, is a bearing, C⁹, which is horizontal and transverse to the length of the machine and receives a shaft, C¹⁰. The lower half of said bearing is formed on the front face of the main portion of said neck while the upper half of said bearing is formed on the detachable forward extension, C⁴, of the neck. When, during the descent of said extension, the upper half of said bearing meets the lower half, the descent of said extension is arrested. In other words, the lower half of said bearing forms a stop for determining the rest position of said forward extension. In axial alignment with the axle, B¹², of the motor is a shaft, C¹¹, extending through and rotatable in the journal, C¹, of the neck, C. On the rear end of the shaft, C¹¹, is a tooth clutch member, C¹², secured immovably to said shaft and directed toward a companion clutch member, C¹³, feathered on the adjacent end of the motor axle, B¹², and adapted to engage the clutch member, C¹². The clutch member, C¹³, is controlled by a clutch bar, C¹⁴, hinged at C¹⁵ to the side wall of the body, B, and coupled to said clutch member, and a shift lever, C¹⁶, which is hinged to the clutch bar at C¹⁷ and has a slide bearing, C¹⁸, in the rear cross wall, B⁸ (Fig. 16). By shifting said shift lever endwise, said clutch members are moved into and out of engagement with each other. When they are in engagement with each other, the shaft, C¹¹, is rotated in unison and in the same direction with the motor axle, B¹². On the forward end of the shaft, C¹¹, is a bevel gear wheel, C¹⁹, meshing with the bevel gear wheel, D³⁰, described further on. On the shaft C¹¹, is a worm, C²⁰, meshing with a worm gear wheel, C²¹, on a shaft, C²², lying in a horizontal plane and slightly oblique to a line perpendicular to the length of the machine and supported in a bearing, C²³, on the detachable forward extension, C⁴, and a bearing, C²⁴, on the upright main portion of the neck, C. The bearing, C²³, is a block held in position by a housing, C²⁵, applied to the front of the upright portion of said extension, C⁴. Said housing extends around the shaft, C¹¹, and covers the worm gear wheel, C²¹, and the bearing, C²³. Near its right-hand end, the shaft, C²², has a worm, C²⁶, meshing with a worm gear wheel, C²⁷, mounted on an upright shaft, C²⁸, resting in an upper bearing, C²⁹, and a lower bearing, C³⁰, the bearing, C²⁹, being in the upper forward extension, C⁴,

and the bearing, C³⁰, being in the main portion of the neck, C. The shaft, C²⁸, passes the left-hand end of the horizontal shaft, C¹⁰, already described as resting in the bearing, C⁹. On said end of the shaft, C¹⁰, is a bevel gear wheel, C³¹, having its teeth directed toward the shaft, C²⁸. On the shaft, C²⁸, wheel, C³¹, are two bevel gears at opposite sides of the bevel gear wheels, C³², which are directed toward each other and adapted to engage the bevel gear wheel, C³¹. The wheels, C³², are slidably endwise on the shaft, C²⁸, but are held against rotation on said shaft by a feather, C³³. A shift bar, C³⁴, engages both of said wheels to keep them at a fixed distance from each other and to make both movable in unison when the shift bar is moved parallel to the shaft, C²⁸. The distance between said wheels is such as to permit their seating to place either in engagement with the wheel, C³¹, or to place both out of engagement with said wheel. On the shaft, C¹⁰, is a worm, C³⁵, which engages a segmental worm gear wheel to be described further on. The purpose of the shafts and gears as above described is to transmit motion from the shaft, C¹¹, to the worm, C³⁵, at reduced velocity and in either direction at the will of the operator.

It has already been described that the neck, C, is joined to the body, B, by placing the journal, C¹, in the bearing, B⁴, in the front cross wall, B⁸. This permits the turning of the neck, C, on the common axial line of the journal, C¹, shaft, C¹¹, bevel gear wheel, C¹⁹, and the motor axle. The group of gearing last above described for transmitting motion from the shaft, C¹¹, to the worm, C³⁵, on the shaft, C¹⁰, is so arranged as to maintain the same relation in whatever radial position the neck may hold on said common axial line, so that said worm, C³⁵, may be rotated in either direction, at the will of the operator, whatever such radial position of the neck may be and when said neck is rotating as well as when it is at rest.

Said neck is turned upon said common axial line by manually-actuated mechanism which will now be described.

At the left of the worm gear wheel, C², already described as being mounted on the inner rear end of the journal, C¹, is an upright shaft, B²⁹, resting in an upper bearing, B³⁰, and a lower bearing, B³¹, the bearing, B³⁰, being formed in the top-plate, B⁷, and the bearing, B³¹, being formed in the bottom of the body, B. On the shaft, B²⁹, is a worm, B³², engaging the worm wheel, C². Above the bearing, B³⁰, there is a socket, B³³, into which the upper end of the shaft, B²⁹, extends, and said end is squared to receive a socket wrench to be turned by the operator for turning the shaft, B²⁹, in

either direction to turn the neck, C, into the desired position on said common axial line. When rotation of the shaft, B²⁰, ceases, the worm, B³², on said shaft, serves as a lock 5 for holding the worm wheel, C², and the neck immovably.

As above stated, the head, D, is supported by the neck. The head comprises a group 10 of parts or members, the form and location and function of which will now be described.

The head is turnable through a range of 180 degrees on an axis which intersects and is perpendicular to the common horizontal axial line above described, (the axial line 15 of the motor axle, B¹², and the transmission axle, C¹¹) while motion is being transmitted to the cutting tool which is carried by the head. These facts call for certain structural peculiarities of the main members of 20 the head.

The head comprises two main casting sections superposed and joined to each other. The low section, D¹, has a horizontal bottom or floor, D⁸, which has straight and 25 parallel side edges and a rear edge formed semi-circular with the axis of the bearing, C⁴, of the neck, C, while as a center, each of the forward corners is rounded on a relatively short radius. On the axis of the bearing, C⁵, said floor has an aperture or bearing, D⁴, receiving the lower end of the bearing, C⁵, so that said section is rotatable on the axial line of the bearing, C⁵. At each 30 side of the longitudinal plane of the machine, said section has an upright wall, D⁵, rising to the full height of said section. At the upper edge of said wall is a horizontal, outward-directed flange, D⁶.

The rear edges of said walls, D⁵, support a 40 wall, D⁷, which is upright and U-shape in horizontal cross section and which has its upper edge extending to or approximately to the height of the walls, D⁵. The lower edge of said wall remains high enough to 45 clear said extension, C³, of the neck, C. The rear portion of said wall is made semi-circular in horizontal cross section, the axis of the bearings, C⁵ and C⁶, being used for a center. The upper portion of the wall, D⁷, 50 is off-set inward to form a seat, D⁸, to support a semi-circular worm rack, D⁹, which meshes with the worm, C³⁵, mounted on the neck, as already described.

Said worm rack is secured to said wall, 55 D⁷, by means of horizontal screw bolts, D¹⁰, extending horizontally through said wall into said rack. By the turning of the worm, C³⁵, as already described, said rack and the head section, D¹, rotate on axis of the bearings, C⁵ and C⁶ already described. The 60 upper head section, D², is similar to the lower head section and has upright front walls, D¹¹, corresponding to the walls, D⁵, of the lower head section and each having at 65 its lower edge a flange, D¹², directed for-

ward and laterally and resting upon the corresponding flange, D⁶, of the lower head section. Said flanges are secured to each other by upright bolts, D¹³, extending through said flanges. Said section comprises 70

a top-plate, D¹⁴, which is of the same general form as the floor or bottom, D⁸, of the lower head section. On the axial line of the bearings, C⁵ and C⁶, said top-plate has a bearing, D¹⁵, extending into the bearing, C⁶, and receiving the upper end of an upright transmission shaft, D¹⁶. Thus the completed head is made turnable on the bearings, C⁵ and C⁶. The top-plate, D¹⁴, has a downward-directed 75 marginal flange, D¹⁷, bearing upon the upper forward extension, C⁴, of the neck, C. Thus a support analogous to a turn-table is given to the head. To minimize lost motion and flexure, a binding plate, D¹⁸, (Fig. 33) is placed flatwise upon the floor or bottom, D⁸, of the lower head section and secured thereto by screws, D¹⁹, and extended rearward around the bearing, C⁵, and across the forward extension, C⁴, and beneath a bracket, D²⁰, seated on the extension, C⁴, the rear edge of said binding plate being made 80 concentric with the bearing, C⁵, so that when the head is turned on said axis, said edge will remain under said bracket. 85

The cutting tool and the members concerned with supporting and actuating the cutting tool are designated the tongue, E. In the forward portion of the head are two upright screw shafts, D²¹, located at opposite sides of and equidistant from the middle 90 upright longitudinal plane of the machine and rest in bearings, D²², in the upper head section and in bearings, D²³, in the lower head section. Each of said shafts has at its upper end a spur gear wheel, D²⁴, keyed to 95 its shaft and meshing with an idle, intermediate spur gear wheel, D²⁵. A yoke plate, D²⁶, extends horizontally across the screw shafts and is penetrated by the necks of 100 said shafts, so that said plate lies between the threads and the spur gear wheels of 105 said shafts. At the middle of said plate is a bearing, D²⁷, which receives the lower end of the axle, D²⁸, of the idle spur gear, D²⁵, while the upper part of said axle has a 110 bearing, D²⁹, in the upper head section. Around the extreme upper end of said shaft, said upper head section is counter-sunk and said shaft is squared to receive a wrench 115 for turning said shaft at the will of the operator. When said shaft is turned, the idle spur gear wheel is turned, and the latter turns the spur gear wheels, D²⁴, and the screw shafts, the rotation of said shafts being in unison and in the same direction. 120 The threads of the screw shafts are in the same direction and of equal size and pitch. Said screw shafts extend through the horizontal tongue block, E¹, which has threads 125 to engage the threads of the screw shafts. 130

When the screw shafts are rotated by the means above described, the tongue block is moved up or down, according to the direction of rotation of said shafts. A rotary cutting tool, C², is journaled in said tongue block in the upright middle longitudinal plane of the machine and in nearly the horizontal position, the front portion of the tool axis being a little lower than the rear end of said axis, in order that the lower side of the cutting portion of the tool (which is tapering) will be in the horizontal position. Around the journal portion, E³, of said tool, is a bushing, E⁴.

On the tongue block, E¹, is a rearward extended bearing, E⁵, receiving the hub of a bevel gear wheel, E⁶, surrounding the shaft, D¹⁶, said wheel being below said bearing and meshing with a bevel gear wheel, E⁷, mounted immovably on the inner end of the journal, E³, of the cutting tool. The bevel gear wheel, E⁶, is slideable on the shaft, D¹⁶, but is held against rotation thereon by a feather, E⁸; and the upper portion of the hub of said wheel has an annular outward-directed flange, E⁹, by which engagement is made in the bearing, E⁵, to prevent said wheel from moving downward away from the tongue block. Motion is imparted to the shaft, D¹⁶, through the bevel gear wheel, D³⁰, which surrounds the upper portion of said shaft and is immovable thereon and meshes with the bevel gear wheel, C¹⁹, on the shaft, C¹¹.

When the motor, B¹¹ is in action and the clutch members, C¹² and C¹³, are in engagement, motion is transmitted through the several parts already described to the bevel gear wheel, E⁷, whereby the cutting tool is rotated. Such engagement remains undisturbed when the elevation of the cutting tool is changed by moving the tongue block, E¹, up or down by rotating the screw shafts as above described; for during such up or down movement of said block, the bevel gear wheel, E⁶, slides on the shaft, D¹⁶, but is held for rotation with said shaft.

Thus the tongue may be raised and lowered (moved toward and from the neck axis) independently of any movement of the head or neck. Furthermore, the tongue may receive sidewise movement by the turning of the head, at the will of the operator, on the axis of the shaft, B¹⁶, by the rotation of the horizontal worm shaft, C¹⁰. Furthermore, the tongue may be given an orbital movement, at the will of the operator, by turning the worm gear wheel, C², and thereby turning the neck, C, on the common axial line of the motor axle and the shaft, C¹¹, the revolutions of said tongue being around said longitudinal or common axial line.

The middle portion of the tongue block E¹, is extended downward, and the adjacent portion of the lower head section is cut away

sufficiently to bring the lower side of the cutting tool to the floor of the mine when the tongue block is in its lowest position. This permits the making of a kerf along the floor level—below the level of the track rails and the ties supporting the track rails.

From the foregoing description, it will be seen that the cutting tool may be given a large variety of movements relative to the neck axis. Whatever position the tool occupies relative to the horizontal axis of the neck, the tool may be carried bodily forward and backward by moving the machine bodily forward and backward, (without turning the machine body) and while the machine is so moving, the tool may be actuated for cutting and making a cut according to the position of the tool relative to the neck axis. Furthermore, the tool may at any time be swung back and forth sidewise in a plane which is tangential to a cylinder having for its axis the axis of the neck and having its diameter equal to twice the distance from the cutting tool to the axis of the neck. And said tangential plane may be brought nearer to or farther from said axial line by turning the pair of screw shafts whereby the tongue block is supported. The neck may be turned into any radial position on its axis and there secured and the cutting tool made to cut relative to said position. The head may also be turned on the shaft, D¹⁶, to any position within its range, and secured in said position. And the tongue may be moved into any position on the screw shafts and held in such position. Furthermore, these various movements may be made simultaneously with varying velocity ratios. All these positions and movements permit cutting in almost every conceivable elevation and direction, including horizontal, upright, oblique, straight courses, and also in curved courses of practically unlimited variety.

Furthermore, the body of the machine may be turned horizontally on its upright axis to give the neck C and all the parts supported thereby bodily horizontal movement through approximately the range indicated by Figs. 40, 41, 42 and 43 of the drawings. By this means, the range of positions of the cutting tool is still further extended. In Fig. 41, the cutting tool is shown placed at right angles to the course of travel of the machine, whereby the machine is adapted to cut in a wall which is parallel to the course of travel of the machine. To similarly cut at the opposite side of the machine, the machine body is to be turned on its upright axis to bring the cutting tool to the opposite side of the machine, the head being then turned on its axis to bring the cutting tool at right angles to the course of travel of the machine.

By combining the movements of the neck and the movements of the parts supported by the neck with the turn-table movements

of the body, the lateral reach of the machine is made very large, and the machine is thereby adapted to cut a wide room.

The machine of this application resembles

- 5 the machine of my co-pending application, Ser. No. 95,690, filed May 5, 1916. In the machine of said application, Ser. No. 95,690, the body of the machine is held parallel to the line of travel of the machine, but is movable up and down relative to the truck, whereby the vertical reach of the cutting mechanism is extended; while in the machine of this application the body is made turnable horizontally for the purpose of extending the lateral reach of the cutting mechanism.

I claim as my invention:

1. In a machine of the nature described, the combination of a body turnable horizontally, means for turning said body, a rotatable neck which is horizontal and parallel to the machine body, means for actuating said neck, a cutting tool, members supported by said neck and comprising a pair of parallel rotatable screws for supporting said tool on said neck for movement on the neck toward and from the axial line of the neck, and means for actuating said cutting tool, substantially as described.
2. In a machine of the nature described, the combination of a body turnable horizontally, means for turning said body, a rotatable neck which is horizontal and parallel to the machine body, means for actuating said neck, a cutting tool, members comprising a pair of parallel screws for supporting said tool on said neck for movement on the neck toward and from the axial line of the neck, and means extending through said neck for actuating said cutting tool, substantially as described.

3. In a machine of the nature described, the combination of a body turnable horizontally, means for turning said body, a rotatable neck which is horizontal and parallel to the machine body, means for actuating said neck, a cutting tool, screw mechanism acting transversely to the axial line of the neck for supporting said tool on the neck for movement on the neck toward and from the axial line of the neck and for swinging the tool on an axis which is forward of the neck and perpendicular to the neck axis, and means for actuating said cutting tool, substantially as described.

4. In a machine of the nature described, the combination of a body turnable horizontally, means for turning said body, a rotatable neck which is horizontal and parallel to the machine body, means for actuating said neck, a cutting tool, members comprising a pair of parallel screws for supporting said tool on said neck for movement on the neck toward and from the axial line of the neck and for swinging the tool

on an axis which is forward of the neck and perpendicular to the neck axis, and means for actuating said cutting tool, substantially as described.

5. In a machine of the nature described, 70 the combination of a body turnable horizontally, means for turning said body, a rotatable neck having an axis which is relatively stationary and horizontal and parallel to the machine body, a cutting tool, screw 75 mechanism carried by said neck and acting transversely to the axial line of the neck for supporting and at the will of the operator moving said tool on the neck toward and from the axial line of the neck, a motor seated on the body of the machine, and means for transmitting motion from the motor to said cutting tool, substantially as described.

6. In a machine of the nature described, 85 the combination of a body turnable horizontally, means for turning said body, a rotatable neck which is horizontal and parallel to the machine body, a cutting tool, members carried by the neck and comprising a pair of parallel screws for supporting and at the will of the operator moving said tool on said neck toward and from the axial line of the neck, a motor seated on the body 90 of the machine, and means for transmitting motion from the motor to said cutting tool, substantially as described.

7. In a machine of the nature described, 100 the combination of a body turnable horizontally, means for turning said body, a rotatable neck which is horizontal and parallel to the machine body, a cutting tool, members comprising a pair of parallel screws for supporting and at the will of the operator moving said tool on said neck toward and 105 from the axial line of the neck, and means extending through said neck for actuating said cutting tool, substantially as described.

8. In a machine of the nature described, 110 the combination of a body turnable horizontally, means for turning said body, a rotatable neck which is horizontal and parallel to the machine body, a cutting tool, screw mechanism acting transversely to the axial line of the neck for supporting and at the will of the operator moving said tool on the neck toward and from the axial line of the neck and for swinging the tool on an axis which is forward of the neck and perpendicular to the neck axis, operator-controlled, 115 power-driven mechanism for effecting said swinging movement, and means for actuating said cutting tool, substantially as described.

9. In a machine of the nature described, 125 the combination of a body turnable horizontally, means for turning said body, a rotatable neck which is horizontal and parallel to the machine body, a cutting tool, members comprising a pair of parallel screws for 130

supporting and at the will of the operator moving said tool on said neck toward and from the axial line of the neck and for swinging the tool on an axis which is forward of the neck and perpendicular to the neck axis, operator-controlled power-driven mechanism for effecting said swinging movement, and means for actuating said cutting tool, substantially as described.

10 10. In a machine of the nature described, the combination of a body, turnable horizontally, means for turning said body, a motor on said body, a head located on said body and rotatable on an axis which is horizontal and parallel to the length of the body, cutting mechanism supported by said head and adjustable thereon bodily toward and from said axis, as far as the distance from said axis to the base of a track supporting the machine, transmission means extending from said motor along said axis into said head and thence to said cutting mechanism, and transmission means for transmitting motion from said motor to the wheels of said truck, substantially as described.

15

20

25

11. In a machine of the nature described, the combination of a body turnable horizontally, means for turning said body, a motor on said body, a head located on said body and rotatable on an axis which is horizontal and parallel to the length of the body, a rotary bar supporting by said head and adjustable thereon bodily toward and from said axis, as far as the distance from said axis to the base of a track supporting the machine, and transmission means extending from said motor along said axis into said head and thence to said rotary cutter bar, substantially as described.

40 12. In a machine of the nature described, the combination of a body turnable horizontally, means for turning said body, a motor on said body, a head located on said body and rotatable on an axis which is horizontal
45 and parallel to the length of the body, a rotary cutter bar supported by said head and adjustable thereon bodily toward and from said axis, as far as the distance from said axis to the base of a track supporting the machine, transmission means extending from said motor along said axis into said head and thence to said rotary cutter bar, and transmission means for transmitting motion from said motor to the wheels of
50 said truck, substantially as described.

13. In a machine of the nature described, the combination of a body turnable horizontally and having a forward, upright cross-wall recessed at its upper edge to form the lower portion of a bearing, a top-plate having at its front edge a downward extension standing above said recess and being upwardly recessed to form the upper portion of a bearing, a neck having a horizontal journal resting in said bearing, means for

rotating said journal and neck; cutting mechanism supported by said neck, and means for actuating said cutting mechanism, substantially as described.

14. In a machine of the nature described, 70
the combination of a body turnable horizontally and having a forward, upright cross-wall recessed at its upper edge to form the lower portion of a bearing, a top-plate having at its front edge a downward extension standing above said recess of the cross-wall and being upwardly recessed to form the upper portion of a bearing, a neck having a horizontal journal resting in said bearing, means for rotating said journal and 80 neck, cutting mechanism, and cutting mechanism actuating means comprising a shaft extending axially through and rotatable in said neck, substantially as described. 85

15. In a machine of the nature described, 85
the combination of a body turnable horizontally and having a forward, upright cross-wall recessed at its upper edge to form the lower portion of a bearing, a top-plate having at its front edge a downward extension standing above the recess of said cross-wall and being upwardly recessed to form the upper portion of a bearing, a neck having a horizontal journal resting in said bearings, worm gearing for rotating said journal and neck, cutting mechanism supported by said neck, and means for actuating said cutting mechanism, substantially as described. 90 95

16. In a machine of the nature described, 100
the combination with a body turnable horizontally and comprising members forming a horizontal bearing, of a neck having a journal resting in said bearing and said neck having an integral, forward-directed extension 105 in which is a bearing perpendicular to the axis of said neck and said neck having a detachable forward extension in which is a bearing axially in line with the bearing in the other forward extension, a head journaled in the bearings of said extensions, 110 worm gearing for turning said head in said bearings, means for turning said journal and said neck, cutting mechanism supported by said head, and means for actuating said cutting mechanism, substantially as described. 115

17. In a machine of the nature described, the combination of a horizontally turnable body comprising members forming a horizontal bearing, a neck having a journal resting in said bearing and said neck having horizontal members each of which has a bearing in alignment with the other of said bearings and perpendicular to the axis of said journal, a head located between said members and journaled in said bearings, means for turning said head on its bearings, cutting mechanism perpendicular to the axial line of said bearings and adjustable on said head toward and from the axial line 120 125 130 135

of said neck, and means for actuating said cutting mechanism, substantially as described.

18. In a machine of the nature described, the combination with a horizontally turnable body comprising members forming a horizontal bearing, of a neck having a journal resting in said bearing and said neck having an integral, forward-directed extension in which is a bearing perpendicular to the axis of said neck and said neck having a detachable forward extension in which is a bearing axially in line with the bearing in the other forward extension, a head journaled in the bearings of said extensions, means for turning said journal and neck, hinged cutting mechanism perpendicular to the axial line of said bearings and bodily adjustable on said head toward and from the axial line of said neck, and means for actuating said cutting mechanism, substantially as described. 70

19. In a machine of the nature described, the combination with a horizontally turnable body comprising members forming a horizontal bearing, a neck having a journal resting in said bearing, said neck having horizontal members each of which has a bearing in alignment with the other of said bearings and perpendicular to the axis of said journal, a head located between said members and journaled in said bearings, means for turning said journal in its bearings, hinged cutting mechanism perpendicular to the axial line of said bearings and adjustable on said head toward and from the axial line of said neck farther than the distance of the supporting faces of the machine from the axial line of said neck, and means for actuating said cutting mechanism, substantially as described. 80

20. In a machine of the nature described, the combination with a horizontally turnable body comprising members forming a horizontal bearing, of a neck having a journal resting in said bearing and said neck having an integral, forward-directed extension in which is a bearing perpendicular to the axis of said neck and said neck having a detachable forward-extension in which is a bearing axially in line with the bearing in the other forward extension, a head journaled in the bearings of said extensions, means for turning said journal and neck, hinged cutting mechanism perpendicular to the axial line of said bearings and adjustable bodily on said head toward and from the axial line of said neck farther than the distance of the supporting faces of the machine from the axial line of said neck, and means for actuating said cutting mechanism, substantially as described. 90

21. In a machine of the nature described, the combination with a horizontally turnable body comprising members forming a horizontal bearing, a neck having a journal rest-

ing in said bearing and said neck having horizontal members each of which has a bearing in alignment with the other of said bearings and perpendicular to the axis of said journal, a head located between said members and journaled in said bearings, means for turning said journal in its bearing for adjustment toward and from the axis of said horizontal bearing, cutting mechanism perpendicular to the axial line of said bearings and supported adjustably by said head, and mechanism for actuating said cutting mechanism, substantially as described. 95

22. In a machine of the nature described, the combination with a horizontally turnable body comprising members forming a horizontal bearing, of a neck having a journal resting in said bearing and said neck having an integral, forward-directed extension in which is a bearing perpendicular to the axis of said neck and said neck having a detachable forward extension in which is a bearing axially in line with the bearing in the other forward extension, a head located between said extensions and journaled in the bearings of said extensions, means for turning said journal and neck, cutting mechanism perpendicular to the axial line of said bearings and supported by said head for adjustment toward and from the axis of said horizontal bearing, and means for actuating said cutting means, substantially as described. 100

23. In a machine of the nature described, the combination of a body turnable horizontally, means for turning said body, a head comprising an upper section and a lower section joined to each other at their meeting edges, means journaling said head on an axis perpendicular to the length of said machine, worm gearing for turning said head on said perpendicular axis, cutting mechanism perpendicular to the axial line of said bearings and supported by said head for adjustment toward and from the axis of said horizontal bearing, and means for actuating said cutting mechanism, substantially as described. 105

24. In a machine of the nature described, the combination of a body turnable horizontally, means for turning said body, a head comprising an upper section and a lower section joined to each other at their meeting edges, means journaling said head on an axis perpendicular to the length of said machine, worm gearing for turning said head on said perpendicular axis, cutting mechanism perpendicular to the axial line of said bearings and supported by said head and bodily adjustable thereon toward and from a line cutting said perpendicular axis perpendicularly, 110 and means for actuating said cutting mechanism, substantially as described. 120

25. In a machine of the nature described, the combination of a body turnable horizontally, means for turning said body, a head 125

comprising an upper section and a lower section joined to each other at their meeting edges, means journaling said head on an axis which is perpendicular to the length of said machine, worm gearing for turning said head on said perpendicular axis, a motor on the machine in operative relation with said worm gearing, cutting mechanism supported by said head for adjustment parallel to the axis on which said head is journaled, and means for actuating said cutting mechanism, substantially as described.

26. In a machine of the nature described, the combination of a body turnable horizontally, means for turning said body, a head comprising an upper section and a lower section joined to each other at their meeting edges, means journaling said head on an axis which is perpendicular to the length of said machine, worm gearing for turning said head on said perpendicular axis, a motor on the machine in operative relation with said worm gearing, cutting mechanism supported by said head and bodily adjustable thereon toward and from a line cutting said perpendicular axis perpendicularly, operator-controlled, power mechanism for making said adjustment, and means for actuating said cutting mechanism, substantially as described.

27. In a machine of the nature described, the combination of a body turnable horizontally, means for turning said body, a head rotatable on an axis which is parallel to the length of the machine, a pair of screw shafts located on the head perpendicular to the course of travel of the machine, a tongue block threaded to said screw shafts, means for rotating said screw shafts, cutting mechanism supported by said tongue block, and means for actuating said cutting mechanism, substantially as described.

28. In a machine of the nature described, the combination of a body turnable horizontally, means for turning said body, a head rotatable on an axis which is parallel to the length of the machine, a pair of screw shafts located on said head perpendicular to the course of travel of the machine, a tongue block threaded to said screw shafts, means for rotating said screw shafts, cutting mechanism supported by said tongue block below the attachment of said block to said screw shafts, and means for actuating said cutting mechanism, substantially as described.

29. In a machine of the nature described, the combination of a body turnable horizontally, means for turning said body, a head rotatable on an axis which is parallel to the length of the machine, a pair of screw shafts supported on said head perpendicular to the course of travel of the machine, a tongue block threaded to said screw shafts and adapted to extend below the supporting

faces of the machine, means for rotating said screw shafts, cutting mechanism supported by said tongue block, and means for actuating said cutting mechanism, substantially as described.

30. In a machine of the nature described, the combination of a body turnable horizontally, means for turning said body, a head rotatable on an axis which is parallel to the length of the machine, a pair of screw shafts located on said head perpendicular to the course of travel of the machine, a tongue block threaded to said screw shafts, and having a middle downward extension, means for rotating said screw shafts, cutting mechanism supported by said extension, and means for actuating said cutting mechanism, substantially as described.

31. In a machine of the nature described, the combination of a body turnable horizontally, means for turning said body, a group of members bodily rotatable on a main horizontal, relatively stationary axis, said group of members comprising a head journaled on an axis which is perpendicular to said main horizontal axis, a transmission shaft in said perpendicular axis, means for rotating said transmission shaft, guiding and supporting means distinct from and parallel and adjacent to said perpendicular axis, cutting means applied to said guiding and supporting means and adjustable thereon toward and from said main horizontal axis, and actuating means extending from said transmission shaft to said cutting mechanism, substantially as described.

32. In a machine of the nature described, the combination of a body turnable horizontally, means for turning said body, a supporting frame, a group of members bodily rotatable on a main horizontal axis, said group of members comprising a head journaled on an axis which is perpendicular to said main horizontal axis, a transmission shaft on said perpendicular axis, means for rotating said transmission shaft, a rotary cutting bar on said head and adjustable toward and from said main horizontal axis, and actuating means extending from said transmission shaft to said cutting bar, substantially as described.

33. In a machine of the nature described, the combination of a body turnable horizontally, means for turning said body, a supporting frame, a group of members bodily rotatable on a main horizontal, relatively stationary axis, said group of members comprising a head journaled on an axis which is perpendicular to said horizontal main axis, a transmission shaft on said perpendicular axis, means for rotating said transmission shaft, cutting mechanism on said head and adjustable toward and from said main horizontal axis, means slidably on and extending from said shaft to said cutting

mechanism for actuating the latter, substantially as described.

34. In a machine of the nature described, the combination of a body turnable horizontally, means for turning said body, a supporting frame, a group of members bodily rotatable on a main horizontal, relatively stationary axis, said group of members comprising a head journaled on an axis which is perpendicular to said horizontal axis, a transmission shaft on said perpendicular axis, means for rotating said transmission shaft, guiding and supporting means distinct from and parallel and adjacent to said perpendicular axis, cutting mechanism applied to said guiding and supporting means and adjustable thereon toward and from said main horizontal axis and adapted to work in planes parallel to said axis, actuating means extending from said transmission shaft to said cutting mechanism, and means for transmitting power to said perpendicular transmission shaft, substantially as described.

25 35. In a machine of the nature described, the combination of a body turnable horizontally, means for turning said body, a supporting frame, a group of members bodily rotatable on a main horizontal, relatively stationary axis, said group of members comprising a head journaled on an axis which is perpendicular to said main horizontal axis, a transmission shaft on said perpendicular axis, means for rotating said transmission shaft, cutting mechanism supported on said head and bodily adjustable thereon toward and from said main horizontal axis, means slideable on and extending from said shaft to said cutting mechanism for actuating the latter, and means on said main axis for transmitting power to said transmission shaft, substantially as described.

36. In a machine of the nature described, the combination of a body turnable horizontally, means for turning said body, a rotatable neck which is horizontal and parallel to the machine body, a cutting tool, members supported on said neck and adapted to support the cutting tool at varying distances from the axial line of the neck, whereby the cutting tool may be carried through an orbital path by the rotation of said neck and the radius of said orbital path may be varied by varying the distance at which said members support said tool from the axial line of the neck, operator-controlled means for actuating said tool supporting members to vary said distance, and means extending along the axis of said neck for actuating said cutting tool, substantially as described.

37. In a machine of the nature described, the combination of a body turnable horizontally, means for turning said body, a tool support rotatable on a horizontal axis,

mechanism for effecting rotation of said support, a cutting tool, members supporting said tool on said support for movement toward and from the axial line of said support, means on said rotatable support for actuating said supporting members for moving said tool toward and from the axial line of the rotary support, and means extending along the axis of said support for actuating said cutting tool, substantially as described.

38. In a machine of the nature described, the combination of a body turnable horizontally, means for turning said body, a tool support rotatable on a horizontal axis, mechanism for effecting rotation of said support, a cutting tool, members supporting said tool on said support for movement toward and from the axial line of said support and for swinging the tool in a plane parallel to said axial line, mechanisms on said rotatable support for actuating said supporting members for moving said tool toward and from the axial line of the rotary support and for swinging the tool in a plane parallel to said axial line, and means for actuating said cutting tool, substantially as described.

39. In a machine of the nature described, the combination of a body turnable horizontally, means for turning said body, a rotary neck resting in a horizontal bearing, a rotary neck shaft in said neck on the axial line of the latter, cutting mechanism supported by said neck and arranged in operative relation with said neck shaft, a motor-driven transmission shaft placed in alignment with and end-to-end with said neck shaft, and clutch mechanism for connecting said transmission shaft and said neck shaft, substantially as described.

40. In a machine of the nature described, the combination of a body turnable horizontally, means for turning said body, a rotary supporting member, an elongated cutting tool, means intervening said rotary member and the cutting tool for carrying the cutting tool in parallel relation to said axial line and for orbital movement around said line and from and toward and into said line, substantially as described.

41. In a machine of the nature described, the combination of a body turnable horizontally, means for turning said body, a rotary supporting member on an axial line which is approximately co-incident with the longitudinal center line of the machine, and an elongated cutting tool carried in parallel relation to said axial line and for orbital movement around said line and from and toward and into said line, substantially as described.

42. In a machine of the nature described, the combination of a body turnable horizontally, means for turning said body, a rotary supporting member, an elongated cutting

- tool, means intervening said supporting member and the cutting tool for carrying the cutting tool in parallel relation to the axial line of the rotary supporting member 5 into said axial line and from said line far enough to permit movement in an orbit larger than the transverse diameter of the machine, whereby said tool, intervening means, and supporting member are adapted 10 to co-operate for cutting along said larger orbit and at all points within said larger orbit for the forming of a tunnel or entry of sufficient cross-section to receive said machine, substantially as described.
- 15 43. In a machine of the nature described, the combination of a body turnable horizontally, means for turning said body, a rotary member, an elongated cutting tool, means intervening said supporting member and the 20 cutting tool for carrying the cutting tool parallel to said axial line for orbital movement around said line and from and toward and into said line and for swinging the tool in a plane parallel to the axial line of the 25 rotary member, substantially as described.
44. In a machine of the nature described, the combination of a body turnable horizontally, means for turning said body, a rotary supporting member on an axial line which is 30 approximately co-incident with the longitudinal center line of the machine, an elongated cutting tool carried parallel to said axial line for orbital movement around said line and from and toward and into said line 35 and to swing in a plane which is parallel to said axial line, substantially as described.
45. In a machine of the nature described, the combination of a body turnable horizontally, means for turning said body, a rotary 40 supporting member, an elongated cutting tool, means intervening said supporting member and said cutting tool for carrying the latter in planes parallel to the axial line of said supporting member for orbital movement around said line and from and toward and into said line, and means for actuating 45 said cutting tool for cutting, substantially as described.
46. In a machine of the nature described, 50 the combination of a body turnable horizontally, means for turning said body, a rotary supporting member, an elongated cutting tool, means intervening said supporting member and said cutting tool for carrying the latter for orbital movement around said line and from and toward and into said line and to swing in planes parallel to the axial line of said supporting member, substantially as described.
- 55 47. In a machine of the nature described,
- the combination of a body turnable horizontally, means for turning said body, a rotatable support which is horizontal and parallel to the machine body, means for turning said support, an elongated cutting tool, 60 members supported on said support for carrying said tool parallel to and from and toward and into the axial line of said neck and in an orbital path which is concentric to said axial line and at any point in the orbit 70 varying the angularity of the tool relative to said axial line, and means for actuating said cutting tool for cutting, substantially as described.
48. In a machine of the nature described, 75 the combination of a body turnable horizontally, means for turning said body, a rotatable support which is horizontal and parallel to the machine body, an elongated cutting tool, members supported by said support and supporting said cutting tool for movement from and toward and into the axial line of the rotatable support and for swinging the tool in a plane which is parallel to said axis, 80 means for effecting said swinging movement, 85 and means for actuating said tool for cutting, substantially as described.
49. In a machine of the nature described, the combination of a body turnable horizontally, means for turning said body, an elongated cutting tool, means for supporting said tool parallel to the machine body and to carry said tool in such parallel relation through orbital paths which are concentric to the middle, longitudinal line of the machine and which range in diameter from zero 90 to the largest, which is of larger diameter than the transverse dimensions of the machine, and means for actuating said cutting tool for cutting, substantially as described. 100
50. In a machine of the nature described, the combination of a body turnable horizontally, means for turning said body, an elongated cutting tool, means for supporting said tool parallel to the machine body and to 105 carry said tool in such parallel relation through orbital paths which are concentric to the middle longitudinal line of the machine and which range in diameter from zero to the largest, which is of larger diameter 110 than the transverse dimensions of the machine, and to swing said tool in planes which are parallel to the axial line of the orbital paths, and means for actuating said cutting tool for cutting, substantially as 115 described.

In testimony whereof I have signed my name, this 6th day of January, in the year one thousand nine hundred and twenty-one.

CYRUS S. OLDROYD.
